BOILER MOUNTING

Robert C. Hopkins, Long Beach, Calif.

Application February 5, 1940, Serial No. 317,230

1 Claim. (Cl. 110—88)

This invention relates to boilers, furnaces, retorts, and the like, and relates more particularly to supports or mountings for boilers and like equipment. A general object of this invention is to provide an inexpensive, particularly effective, portable boiler mounting.

In installing boilers in oil fields and similar places it is necessary to build suitable foundations of concrete, or the like, to mount the boilers. These foundations are expensive and require considerable time to build. If it is desired to move a boiler to a new location a new foundation must be provided and the foundation at the original installation is useless and, therefore, abandoned.

Another object of this invention is to provide a portable boiler mounting that may be quickly installed without expensive foundations and that may be readily moved when the boiler is moved to a new location.

Another object of this invention is to provide a boiler mounting of the character mentioned that is in the form of a single, compact, readily transported unit.

Another object of this invention is to provide a portable unitary boiler mounting of the character mentioned that is complete, including dependable supporting elements for the boiler proper, means for supporting the burner, and a dependable lining of refractory material.

Another object of this invention is to provide an improved boiler mounting that increases the combustion and heating efficiency of the burner and, therefore, the efficiency of the boiler.

Another object of this invention is to provide a boiler mounting of the character referred to that supports the burner below the fire box of the boiler to provide a larger combustion chamber, to maintain the flames under the boiler, and to prevent the direct engagement of the flames with the plates and tubes of the boiler.

The various objects and features of my invention will be fully understood from the following detailed description of typical preferred forms and applications of the invention, throughout which description reference is made to the accompanying drawings, in which:

Fig. 1 is a fragmentary side elevation of a typical boiler with its burner assembly, illustrating the manner in which the mounting of the present invention supports the boiler and burner assembly, the lower portion of the boiler and the mounting being in vertical cross section. Fig. 2 is an enlarged fragmentary vertical detailed sectional view of the mounting body and its lin-

ing. Fig. 3 is an enlarged perspective view of the improved boiler mounting. Fig. 4 is an enlarged fragmentary vertical detailed sectional view of the mounting. Fig. 5 is a reduced vertical sectional view of another form of the invention with a part of the boiler in elevation.

The boiler mounting of the present invention may be employed to support boilers of various types and, of course, may be modified somewhat in construction for special or specific installations. In Fig. 1 of the drawings I have shown a typical oil field boiler B having the usual "leg" or fire box 11 and the tube or body 10 extending horizontally from the upper end of the fire box. The fire box 11 is open at its lower end and, in accordance with the usual practice, its walls comprise spaced connected plates. The boiler burner assembly 12 shown in the drawings is a fluid fuel burner comprising a rectangular frame 13, a plurality of jets 14 supported in the frame 13 to project from its upper surface and the fuel supply 15 provided with the usual air or draft control means 16. It is to be understood that the boiler and burner structure illustrated are typical and are not to be taken as limiting or restricting the invention.

The improved boiler mounting of the invention shown in Figs. 1 to 4, inclusive, may be said to comprise, generally, a body 17, legs 18 for the body 17, a lining 19 for the body 17, and a water or steam coil 20 in the lining 19.

The body 17 is provided to support the boiler B being intended for arrangement under the "leg" or fire box 11. In accordance with the invention the body 17 is a simple, rigid structure shaped to conform generally to the lower end of the fire box 11. It is preferred to form the body 17 of I-beams and in the case illustrated the body 17 comprises two side members 21 and two end members 22 formed of I-beam stock. The members 21 and 22 are connected to form a structure that is square or rectangular in plan view and proportioned to substantially conform to the lower end of the boiler fire box 11. The end members 22 extend between and connect the spaced side members 21 and in the particular arrangement illustrated the upper and lower flanges 23 of the end members 22 are cut back at their extremities to allow the webs of the members 22 to come against the webs of the side members 21. The upper and lower flanges 24 of the side members 21 preferably occupy the same horizontal planes as the flanges 23. The members 21 and 22 are rigidly connected. Welding 25 may join the flanges 23 and 24 and the ver-

tical webs of the members 21 and 22. The upper flanges 23 and 24 of the body members present large horizontal surfaces on which the fire box 11 may bear and which facilitate the ready connection of the boiler to the body 17. Openings 26 may be provided in the webs of the members 17 adjacent the ends of the body 17 to facilitate the lifting and transporting of the assembly.

The legs 18 serve to support the body 17 and form convenient, effective means for mounting the burner assembly 12. The legs 18 may be sections of I-beams of selected width arranged horizontally to have base flanges 27 and top flanges 28. The top flanges 28 are welded or otherwise fixed to the lower flanges 24 of the side members 21 while the base flanges 27 may rest on foundation blocks or may be cast in concrete or the like. Vertical webs or braces 29 may extend between the flanges 27 and 28 at the outer sides of the legs 18 to strengthen the legs. The legs 18 may be flush with the opposite ends of the side members 21. The inner sides of the legs 18 are provided with horizontal shelves or brackets 30. The brackets 30 are fixed to the legs 18 as by welding and are spaced between the upper and lower ends of the legs. The brackets 30 serve to mount or support the burner assembly 12 in the base. Tie bolts 31 pass through vertical openings in the brackets 30 and transverse members 32 of the burner assembly 12 to secure the burner assembly in the boiler mounting. The burner assembly 12 may be supported where the upper side of its frame 13 engages against the lower flanges 23 and 24 of the body 17 and where the lower side of its frame is clear of the ground or support. It will be observed that the legs 18 support the burner assembly 12 so that the jets 14 are in the lower portion of the body 17 and a substantial distance below the fire box 11.

The lining 19 serves to protect the body 17 against the burner heat and further serves to contain or carry the coil 20. The lining 19 covers the inner surfaces of the body members 21 and 22 and as illustrated may be of substantial horizontal thickness to project inwardly beyond the flanges 23 and 24. The upper and lower surfaces of the lining 19 may be flush with the corresponding surfaces of the upper and lower flanges 23 and 24. The lining 19 may be formed of fire clay, fire bricks, or other refractory material, and may be cast or formed in the body 17. It will be observed that the inner flanges or inner flange parts of the body members 21 and 22 serve as effective supports and retainers for the lining 19. The lining 19 covering the inner side of the body 17 encloses a space for the flames of the burner unit 12 and thus defines a lower extension of the fire box 11. Where the lining 19 projects inwardly beyond the walls of the fire box 11, fire bricks 34 or the like may be stacked or laid on the top of the lining to line and protect the walls of the fire box. Plates 9 may be welded or otherwise secured to the lower flanges 23 and 24 to assist in supporting the lining 19 in the body 17 and the lining may have internal reinforcements as required.

The coil 20 may be employed as a pre-heating coil for the feed water of the boiler B or if desired may be employed as a superheater for the steam generated by the boiler. In accordance with the invention the coil 20 is cast or embedded in the lining 19 and it is preferred to locate or arrange the coil to lie relatively close to the inner surface of the lining. The coil 20 may be of any se-

lected capacity and may have as many convolutions as required. The inlet and outlet ends 35 of the coil 20 extend through openings in the body 17 to be conveniently connected with the water or steam lines. The fluid handled by the coil 20 is, of course, heated by the heat conducted through the inner portion of the lining 19.

It is believed that the utility and practicability of the boiler mounting of the present invention will be understood from the foregoing detailed description. In installing the boiler B the mounting may be readily transported and installed as a unit. If desired the burner assembly 12 may be secured in the boiler mounting to be transported therewith. The mounting is quickly and easily installed by merely mounting its four spaced legs 18. The legs 18 may be arranged on any selected or available support or may be cast in blocks or a floor of concrete, or the like. With the boiler mounting in place the boiler B is quickly installed by merely resting its fire box 11 on the base body 17 and if desired securing the fire box to the mounting body. In the operation of the boiler the fuel is supplied to the jets 14 in the usual manner and the heat of the burner flames serve to generate the steam. The jets 14 are located in the lower portion of the body 17 and are therefore below the fire box 11. Thus the improved mounting of the invention provides a larger combustion space and lowers the flames in the fire box to increase the efficiency and capacity of the boiler. With the flame lowered by reason of the location of the burner assembly in the improved mounting the flames are lower in the boiler structure minimizing injury to the boiler plates or tubes. The coil 20 embedded in the lining 19 is available as a preheater for the feed water or as a superheater for the steam. When the boiler is to be moved it may be readily detached from the improved mounting and the mounting may be freed for transportation. The mounting, with or without the attached burner assembly 12, is a compact, readily transported unit. The mounting may be employed to mount or support the boiler B in its new location.

Fig. 5 illustrates a form of the invention suitable where a high pressure burner 14^a is to be employed. In the construction of Fig. 5 a pit 50 is provided under the leg or fire box 11 of the boiler B and the boiler mounting of the invention is positioned in the pit. The portable boiler mounting of Fig. 5 comprises a body 17^a of suitable height designed to fit the pit 50 and to accommodate the lower end of the fire box 11. The body 17^a is of suitable construction, for example, it may be made up of a series of superimposed rectangular sections 51. The sections 51 are formed of I-beams or other stock and are suitably connected to form a rigid unit. The height of the body 17, of course, depends upon the depth of the pit 50. The mounting body 17^a may rest on the bottom of the pit 50 and the upper end of the body may extend above the pit to receive and support the lower end of the fire box 11. A refractory lining 19^a similar to the lining 19 is provided on the inner surface of the body 17^a and a suitable lining 53 may be provided on the bottom of the pit 50. The high pressure burner 14^a enters through an opening 54 in the body 17^a and the lining 19^a to discharge in the hollow body. The burner 14^a may be directed downwardly and inwardly in the mounting.

The boiler mounting, shown in Fig. 5, has substantially the same features and uses as the previously described mounting. The body 17^a

carrying the lining 19^a, which may or may not embed the coil 20, is readily transported as a unit and may be quickly installed in the pit 50. The body 17^a arranged in the pit forms a convenient dependable mounting for the boiler B. If the boiler is to be moved the body 17^a carrying the lining 19^a and the coil 20, where the coil is employed, may be removed from the pit and transported to the new location of the boiler to again mount the boiler.

Having described only typical preferred forms and applications of my invention, I do not wish to be limited or restricted to the specific details herein set forth, but wish to reserve to myself any variations or modifications that may appear to those skilled in the art or fall within the scope of the following claim.

Having described my invention, I claim:

A portable mounting for a boiler having a fire box open at its lower end, the mounting comprising spaced side I-beam members, spaced end I-beam members extending between and rigidly joined with the side beam members to form a rigid tubular body conforming generally to the lower end of the fire box, the upper flanges of the I-beam members forming a support for the fire box and the interior of the body communicating with and forming a downward continuation of the interior of the fire box, a refractory lining on the interior of the body between the upper and lower flanges of the beam members, and legs secured to and extending downwardly from certain of said lower flanges to support the body.

ROBERT C. HOPKINS.
